1

This invention relates to the hydrocatalytic desulphurisation of petroleum hydrocarbons.

Among the processes which are known for the removal of organically combined sulphur from petroleum hydrocarbons is the so called hydrofining process in which the petroleum hydrocarbons to be desulphurised are passed in admixture with hydrogen over a sulphur-resistant hydrogenation catalyst at elevated temperature and pressure whereby the organically combined sulphur is converted into hydrogen sulphide which may readily be removed from the treated hydrocarbons the properties of which are not otherwise appreciably affected. This process is technically effective for the removal of organically combined sulphur from petroleum hydrocarbons but is not commercially attractive in view of the cost of supplying the considerable quantity of hydrogen consumed in the process. It was also known that the hydroforming process produced hydrogen and at the same time effected a considerable degree of desulphurisation, but by its very nature this process is not applicable in cases where it is desired to desulphurise feedstocks, such as gas oils and aromatic extracts, without appreciably affecting the properties of the feedstock other than changes consequent upon the removal of the organically combined sulphur as hydrogen sulphide. Desulphurisation processes are also known in which a substance capable of supplying hydrogen under the conditions of the desulphurisation reaction is added to the feedstock to be desulphurised, but this is only a special case of hydrofining and suffers from the disadvantage of the cost of supplying the hydrogen donor and from the additional disadvantage that the through-put of the feedstock is reduced by the addition of the considerable quantity of hydrogen donor necessary to supply sufficient hydrogen.

It was then discovered that by careful control of the temperature and pressure and by using a sufficiently active dehydrogenation-hydrogenation catalyst, it was possible to derive sufficient hydrogen by dehydrogenation of naphthenes contained in the feedstock to enable sufficient of the organically combined sulphur in the feedstock to be converted into hydrogen sulphide, under the same temperature and pressure conditions, to constitute an effective desulphurisation process. This process has been "autofining" and it has the considerable advantage as compared with hydrofining that all the hydrogen required for desulphurisation is derived from the feedstock itself. It was surprising to find that conditions existed under which the two reactions of dehydrogenation of naphthenes and hydrogenation of organic sulphur compounds could

2

proceed simultaneously to the extent necessary to provide a satisfactory catalytic desulphurisation process. The process was found to be applicable to a wide variety of feedstocks ranging from naphthas to wax distillates under the following set of conditions:

Pressure _____ p. s. i. ga. 50-250
Temperature _____ ° F. 750-800
Space velocity _____ v./v./hr. 1.0-5.0
10 Recycle rate _____ C. F./B. 2000-4000

The preferred catalyst for use in the autofining process is of the so-called cobalt molybdate type which comprises mixtures of the oxides of cobalt and molybdenum, or chemical compounds of cobalt, molybdenum and oxygen, or mixtures of one or both of said oxides with said compounds either alone or incorporated with a support. It has been found that there is a period at the commencement of each run during which the gas make is negligible or non-existent and the desulphurisation is not at its maximum. This low dehydrogenating activity of the catalyst is more noticeable at low feedstock velocities and with the heavier feedstocks. It was discovered that the non-activity of the catalyst during the early hours on stream could be largely overcome by subjecting the catalyst to the action of hydrogen sulphide or hydrogen sulphide-containing gas prior to its use in the autofining process.

The regeneration of the used catalyst may be carried out by burning off the carbon and sulphur deposits with either a nitrogen/air or steam/air mixture. The following conditions may be employed for regeneration.

Inlet temperature _____ ° F. 800-850
Steam or nitrogen flow _____ v./v./hr. 700-900
Air flow _____ v./v./hr. 50-60
40 Inlet oxygen _____ percent mol. 1 to 1.5

The inlet oxygen concentration is controlled to keep the catalyst bed temperature below 1100° F. Regeneration restores the activity of the catalyst completely and it has been found that a large number of regenerations has no effect on the activity or properties of the catalyst.

The autofining process may be operated by setting the pressure in the autofining zone at a predetermined level and thereafter withdrawing from the system gas in excess of that required to maintain the predetermined pressure. In this case, there is a continuous make of hydrogen indicating that the hydrogen produced in the dehydrogenation reaction is not being fully utilized in the desulphurisation reaction. An improved method of operation was therefore developed in which the hydrogen-containing gaseous

3

fraction is recycled to the reaction zone and the pressure therein allowed to rise to an equilibrium pressure at which the hydrogen evolved equals the hydrogen consumed. This method of operation results in a greater degree of desulphurisation and increased on-stream hours for a product of given sulphur content.

The autofining process may be carried out in a static bed reactor or by the use of the moving bed or fluid catalyst techniques.

In the autofining of the light straight-run feedstocks, such as naphthas and kerosines, there is a considerable excess gas make which contains upwards of 80 per cent mol. hydrogen. Desulphurisation of these light feedstocks is of the order of 99 per cent at pressures as low as 100-200 p. s. i. ga., so that there would be no advantage in increasing the pressure or in operating according to the equilibrium pressure method above referred to. It is well-known that in order to desulphurise heavier feedstocks, such as wax distillates, crude oil and reduced crude, it is necessary to provide large quantities of hydrogen from external sources.

According to the present invention, the excess gas obtained from autofining light petroleum feedstocks, such as naphthas and kerosines, is used to supply hydrogen to an independent hydrogenation zone.

By an autofining process is meant a process in which a petroleum feedstock is passed in vapour form in admixture with hydrogen over a catalyst which combines activity for the dehydrogenation of naphthenes to aromatics with activity for the hydrogenation of organic sulphur compounds and which is not poisoned as a catalyst by the presence of sulphur compounds, under conditions of temperature and pressure which are correlated so that dehydrogenation of naphthenes contained in the feedstock is effected to an extent not substantially in excess of that required to produce sufficient hydrogen to convert organically combined sulphur in the fraction into hydrogen sulphide and to maintain the pressure in the reaction zone, the hydrogen and hydrogen sulphide being separated from the treated feedstock and the hydrogen recycled to the reaction zone as the sole source of hydrogen to said zone.

The excess gas from the autofining zone may not be sufficient to supply all the hydrogen required in the hydrogenation zone but will in any case represent a considerable saving in hydrogen.

The independent hydrogenation zone may consist of a hydrofining zone for the treatment of heavier petroleum feedstocks, such as wax distillate, crude oil and reduced crude, that cannot be satisfactorily autofined. On the other hand, the hydrogenation zone may be for carrying out a well-known hydrogenation process, such as the conversion of diisobutylene to isooctane.

According to a preferred method of carrying the invention into effect, a crude oil is fractionated for the recovery of a light fraction, which is autofined and a residue, the excess gas make from the autofining stage being used to hydrofine the residue or a heavy fraction thereof.

The invention will now be described with reference to the accompanying diagrams, wherein Figures 1-3 illustrate different methods of carrying the invention into effect.

In the methods illustrated in Figures 1 and 2, a naphtha-kerosine fraction is autofined and the excess gas is used to hydrofine a wax distillate fraction. The relative proportions by volume

4

of naphtha-kerosine and long wax distillate cut are approximately 2:1.5 and 2:1 for two representative Iranian crudes, although this may vary considerably according to the length of the wax distillate cut. Thus, if the excess gas make is 50 cubic feet per barrel when autofining the naphtha-kerosine blend, then there are available 75-100 cubic feet per barrel for the desulphurisation of the wax-distillate or other heavy fraction. Two methods of utilising this excess hydrogen-containing gas for the desulphurisation of wax distillates are illustrated in Figures 1 and 2.

Referring first to Figure 1, the naphtha-kerosine blend is fed by a pump 1 to the preheater 2 after admixture with the recycle gas. The hot vapours pass downwards through the autofining reactor 4 and after passing through the cooler or heat exchanger 5 are separated into two phases in the vessel 6. The liquid phase which contains the desulphurised kerosine-naphtha blend is passed via line 7 to a stabiliser and distillation unit for separation of the fractions as desired. The gas phase which contains upwards of 80 per cent mol. hydrogen is split into two streams, one being recycled through line 8 and the booster 3 to maintain the conditions in the reactor 4 while the other, the excess gas, passes through a control valve 9. The wax-distillate fraction is fed by a pump 10 into admixture with the excess gas from the autofining system and passes to the preheater 11 via line 16. The preheated products pass downward over the catalyst bed 12 through a pressure control valve 13 and cooler 14 to the separator 15. The liquid phase is run off via line 17 for stabilisation for removal of hydrogen sulphide and the gases vented via line 18.

The reactor 4 and its accompanying system are operated at a pressure of 220 pounds per square inch pressure and the excess gas fed into the wax-distillate stream at +200 pounds per square inch. The wax distillate section therefore operates as a once through hydrofining process i. e. with no recycle, and pressure is supplied from the first section so that an economic hydrogen partial pressure is maintained in the second section. If necessary, the relative proportion of hydrogen in the excess gas can be increased by scrubbing out the hydrocarbons but this is not essential, neither is it essential to remove hydrogen sulphide from the recycle or excess gas. The following is a specific example of this method of operation:

EXAMPLE 1

Autofining section

60 Feedstock	Iranian naphtha-kerosine fraction
	8-48% vol. on crude.
Catalyst	Mixed cobalt and molybdenum oxides on alumina.
Pressure	220 p. s. i. ga.
Temperature	780° F.
Space velocity	2.0 v./v./hr.
Gas recycle rate	2500 S. C. F./B.
Gas hydrogen content	89-90% vol.
Excess gas	25 S. C. F./B.
Sulphur content feed	23% wt.
Sulphur content product	.002% wt.
Sulphur removal	99%.

5

Wax-distillate desulphurisation

Feedstock	Iranian wax-distillate cut 72% 82% vol. on crude.
Catalyst	Mixed cobalt and molybdenum oxides on alumina.
Duration of run	50 hours.
Pressure	200 p. s. i. ga.
Temperature	750° F.
Space velocity	1.0 v./v./hr.
Inlet gas rate	100 S. C. F./B.
Sulphur content feed	1.5% wt.
Sulphur content product	0.681% wt.
Sulphur removal	55%.

The method illustrated in Figure 2 is essentially the same as that illustrated in Figure 1, the only difference being the provision of a compressor 19 between the two sections to enable the wax-distillate desulphurisation to be carried out at a higher pressure and thereby increase the sulphur removal. The amount of excess gas from the autofining section can be controlled, within limits, by adjustment of the space velocity. The following is a specific example of this method of operation:

EXAMPLE 2

Autofining section

Feedstock	Iranian naphtha-kerosine fraction 8-48% vol. on crude.
Catalyst	Mixed cobalt and molybdenum oxides on alumina.
Pressure	150 p. s. i. ga.
Temperature	780° F.
Space velocity	1.0 v./v./hr.
Gas recycle rate	2500 S. C. F./B.
Gas hydrogen content	85-90% mol.
Excess gas	50 S. C. F./B.
Sulphur content of feed	0.25% wt.
Sulphur content of product	<.002% wt.
Sulphur removal	>99%.

Wax-distillate desulphurisation

Feedstock	Iranian wax-distillate cut 72% 82% vol. on crude.
Catalyst	Mixed cobalt and molybdenum oxides on alumina.
Duration of run	50 hours.
Pressure	500 p. s. i. ga.
Temperature	750° F.
Space velocity	1.0 v./v./hr.
Inlet gas rate	200 S. C. F./B.
Sulphur content of feed	1.5% wt.
Sulphur content of product	0.3% wt.
Sulphur removal	80%.

It will be noted that to increase the excess gas make in the autofining section, the space velocity and pressure have been decreased.

Referring now to Figure 3, crude petroleum stabilised to 20° C. is fed via preheater 20 to the

6

fractionating tower 21 where a naphtha-kerosine cut boiling between 20° and 250° C. is taken overhead through condenser 22 to the reflux drum 23.

Some of the naphtha-kerosine is returned to the tower as reflux by the reflux pump 24, the remainder being fed by the feed pump 25 to the preheater 26. The naphtha-kerosine, together with the recycle gas, is brought up to reaction temperature and passes into the reactor 27. The autofined product from the reactor passes out through a waste heat boiler 28 to a knock-out tower 29. The pressure on the waste heat boiler is controlled to give an inlet temperature into the knock-out tower such that the kerosine is condensed whilst the naphtha and recycle gas pass off the top of the knock-out tower through a cooler 30 to a separator 31. There the recycle gas separates from the liquid naphtha and is recycled by means of the gas booster 32 to the preheater inlet. Further control of the knock-out tower is effected by returning some of the cold naphtha from the separator as reflux by the pump 33. The kerosine passes from the base of the knock-out tower through a cooler 34 to storage. The naphtha passes from the separator to a conventional stabiliser (not shown) where the dissolved hydrogen sulphide is removed. The excess gas, over and above that required to maintain the system under pressure, is released through the pressure control valve 35 to the compressor 36. Here, it is compressed to the required operating pressure and passes via the flow controller 37 into the preheater inlet line, where it meets the residue from the fractionator 21 and passes into the preheater 38. The gas-residue mixture is brought up to the reaction temperature in the preheater 38 and passes into the reactor 39.

The desulphurised product and the gas pass out via a pressure control valve 40, which can be used to control the preheater and reactor pressure or which can, if required, be bypassed. The hydrocarbon-hydrogen stream passes through a cooler 41 to a separator 42, where the gas separates from the liquefied product. The gas can either be vented via the pressure controller 43 or be recycled by the recycle booster 44 to the preheater inlet.

The desulphurised residue is passed from the separator 42 via a stabiliser (not shown) to remove dissolved hydrogen sulphide to storage. If required, fresh hydrogen from an external source may be injected into the suction of the compressor 36 through line 45. The use of control valves 40, 43 and 37 and the gas recycle booster 44 depends on whether it is desired to operate with or without a gas recycle system and/or hydrogen added from an external source. This may be summarised as follows:

Case 1.—Recycle system without external hydrogen.—Booster 44 and pressure controller 43 in use. Valves 40 and 37 by-passed.

Case 2.—Recycle system with external hydrogen.—Booster 44, pressure controller 43 and flow controller 37 in use. Valve 40 by-passed.

Case 3.—Once-through system without external hydrogen.—Valve 40 in use, valves 43 and 37 by-passed and booster 44 shut down.

The following results were obtained for stabilised 20° C. Iranian crude:

Yield distillate (naphtha-kero.) B./B. stable crude=.43.

Yield residue (>250° C.) B./B. stable crude=.57.

Conditions for naphtha-kero. autofining

Pressure, p. s. i. ga.	100
Reactor temp., °F.	800
Space velocity, v./v./hr.	1.0
Recycle rate, S. C. F./B.	4000
Total sulphur in feed, percent wt.	.089
Total sulphur in naphtha product	>.001
Total sulphur in kerosine	.001
Sulphur removal, percent	98.8
Excess gas (approx. 80 mol. percent H ₂)	150
S. C. F./B. naphtha-kerosine	
=64.5 S. C. F./B. stable crude.	
=113 S. C. F./B. residue.	

Conditions for residue desulphurisation

	Case 1	Case 2	Case 3
Pressure, p. s. i. ga.	300	1,000	500
Reactor Temp., °F.	750	750	750
Space Velocity, v./v./hr.	1.0	1.0	1.0
Recycle Rate, S. C. F./B.	4,000	4,000	once through.
External H ₂ , S. C. F./B.	nil	80	nil
Total Sulphur in Feed, percent wt.	1.81	1.81	1.81
Total Sulphur in Product	1.09	0.36	0.9
Sulphur Removal, percent	40	80	50

Inspection data on residue before and after desulphurisation (conditions as for Case 2)

RESIDUE (BEFORE)

Fraction	Below 250° C.	250-350° C.	350° C.
Yield, percent wt. on stable crude		19.9	41.2
Sulphur, percent wt.		0.85	2.25

DESULPHURISED RESIDUES

	Below 250° C.	250-350° C.	350° C.
Yield, percent wt., on stable crude	4.0	25.2	31.9
Sulphur, percent wt.	0.002	0.2	0.53

The product distribution in Cases 1 and 3 will be similar to Case 2, except that less lower boiling material will be formed.

Among the advantages of the process according to the invention are the production of a naphtha-kerosine fraction of low sulphur content, and of a reduced crude of low sulphur content, of lowered viscosity and with an increased content of lower boiling material.

We claim:

1. A process for the recovery of sulphur-free products from naphthene-containing crude petroleum by the hydrocatalytic desulphurisation process without the need for an extraneous source of hydrogen, which comprises fractionating the crude petroleum for the recovery of a selected naphthene-containing low-boiling fraction and a residue, passing said low-boiling fraction in admixture with hydrogen derived solely from said fraction to a first desulphurisation zone wherein it is contacted with a sulphur-resistant dehydrogenation-hydrogenation catalyst which is immune

to sulphur poisoning and combines activity for the dehydrogenation of naphthenes to aromatics with activity for the hydrogenation of organically combined sulphur in said fraction to hydrogen sulphide at a selected temperature within the range 750-800° F. and a selected pressure within the range 50-250 p. s. i. ga., said temperature and pressure being correlated so that organically combined sulphur in said fraction is converted into hydrogen sulphide and hydrogen is produced by dehydrogenation of naphthenes contained in said low-boiling fraction in an amount in excess of that required to convert organically combined sulphur contained in said low-boiling fraction into hydrogen sulphide and maintain the necessary partial pressure of hydrogen in said zone, separating hydrogen sulphide and a hydrogen-rich gas mixture from the products of said first desulphurisation zone, recycling a portion of said hydrogen-rich gas mixture to said first desulphurisation zone to constitute the whole of the hydrogen supplied to said zone, the hydrogen recycle rate being sufficient to maintain the necessary partial pressure of hydrogen in said zone therein, passing another portion of said hydrogen-rich gas mixture in admixture with said residue to a second desulphurisation zone wherein said residue is contacted with a sulphur-resistant hydrogenation catalyst and hydrogen of the mixture at a temperature and pressure suitable for hydrofining of said residue whereby organically combined sulphur contained in said residue is converted into hydrogen sulphide, said hydrogen-rich gas mixture constituting the sole source of hydrogen supplied to said hydrofining stage, separating hydrogen sulphide from the products of said second desulphurisation zone, and recovering a substantially sulphur-free product from both said desulphurisation zones.

2. A process in accordance with claim 1 in which a hydrogen-rich gas mixture is obtained from the second desulphurisation zone and is recycled to the second desulphurisation zone.

3. A process in accordance with claim 1 wherein the recovered low-boiling fraction comprises the naphtha and kerosene fractions.

4. A process in accordance with claim 1 wherein the sulphur-resistant dehydrogenation-hydrogenation catalyst is a cobalt molybdate type.

5. A process in accordance with claim 1 wherein the low-boiling fraction comprises the naphtha and kerosene fractions and the dehydrogenation-hydrogenation catalyst is a cobalt molybdate type.
